England

Application January 14, 1932, Serial No. 586,542,
and in Great Britain January 14, 1931

5 Claims. (Cl. 171—118)

This invention relates to reciprocating prime movers or pumps, hereinafter for convenience termed engines, and more particularly to arrangements of the kind comprising a pair of such engines arranged by means of synchronous dynamo-electric machines respectively coupled to the two engines and electrically connected with one another to run interlocked at the same speed with the direction of rotation of one engine bearing a definite relationship to the direction of rotation of the other engine and with reciprocating parts of the engines at any instant in predetermined relative positions or at predetermined relative points of their cycles of operation. Such arrangements are useful for the purpose reducing vibration. The precise way in which the engines should be interlocked depends on the particular circumstances of the case, but, for example, with a pair of similar Diesel engines mounted side by side in a ship and arranged symmetrically and having their crank shafts parallel or substantially parallel with respect to the vertical plane extending longitudinally of the ship and containing the centre of gravity of the latter it has been proposed to cause the engines to run in opposite directions with the reciprocating parts of corresponding cylinders of the respective engines at any instant of time similarly disposed so that the power strokes for the two cylinders occur simultaneously. It has also been proposed in order to reduce vibration to fit the twin propellers of a vessel so that they rotate directly out of synchronism with one another. For example, in the case of four bladed propellers it was suggested that when two blades of one propeller were in a vertical line, two blades of the other propeller should be displaced by an angle of 45° from the vertical position. In any case the pair of engines must be synchronized, that is to say they must be caused to run in such a way that the reciprocation or cycle of operations of a piston of one engine occurs with or substantially with a definite phase relationship with respect to the reciprocation or cycle of operations of a piston of the other engine and the chief object of the invention is the provision of means whereby this result may readily be obtained with little effort on the part of the operator.

50 The invention will now be described by way of example with reference to the accompanying diagrammatic drawings in which Figure 1 is a diagram of connections showing the invention applied to two Diesel engines adapted to propel a ship, the means for operating certain control contacts being omitted, whilst Figures 2, 3, 4 and 5 illustrate various methods of operating the said contacts.

In Figure 1 the engines 1 and 2 are coupled directly to the propeller shafts 3 and 4 and are arranged to drive them in opposite directions. The engines which are eight cylinder four stroke Diesel engines, are similar to one another and are disposed symmetrically on opposite sides of centre line of a ship with their crank shafts 65 parallel to or substantially parallel to that centre line, and it is arranged for the cycle of operations of corresponding cylinders of the two engines to occur synchronously. If desired a higher speed may be obtained, but the normal maximum 70 engine speed is 280 R. P. M.

The engines 1 and 2 are arranged respectively to drive two alternating current synchronous dynamo-electric machines 5 and 6 that may be electrically connected and are arranged to operate in such a way that the cycles of operation of corresponding cylinders of the respective engines occur synchronously, means being provided which are adapted automatically to synchronize the machines 5 and 6 whilst corresponding pistons of the respective engines 1 and 2 are at similar points of their cycles of operation. In the form illustrated the synchronizing arrangement comprises means which tend to effect synchronization of the machines 5 and 6 when the latter 75 are in a state suitable for synchronization, and means which prevent synchronization of the machines unless the moving parts of the engines 1 and 2 are respectively in or near the proper 80 relative positions.

The machines 5 and 6 are in the form of 80 kilowatt 24 pole three phase alternators, the field windings being excited from the busbars 10 and 11 connected to a suitable direct current power supply through the switch 7, the field rheostats 95 8 and the slip rings 9.

It is arranged for the synchronization of the alternators 5 and 6 to be effected by exciting the field windings of the alternators and by connecting the alternators in parallel through conductors 12, 13 and 14, the connection between the machines first being through a 3-phase choker 15, which, when the voltages of the two machines are substantially equal and the corresponding phase voltages are substantially in opposition, is short-circuited. The connection together of the two alternators through the choker is effected by means of a synchronizing contactor 16 the operating coil 17 of which is controlled by voltage responsive relay means. The control may be exerted by 110

a single voltmeter relay, but it is preferred to use two induction disc type relays 18 and 19 each of which is provided with two shaded pole electromagnets, one an opening electromagnet provided with a coil 20, the other a closing electromagnet provided with a coil 21. The electromagnets act in opposite directions on the disc 22, and with equal currents flowing through the energizing coils 20 and 21 of the electromagnets the opening electromagnet exerts a torque which is, say, 5 or 10% less than the torque exerted by the closing electromagnet which tends to rotate the spindle 23 of the relay against the force of a controlling spring 24 and thereby to move a contact 25, carried by the spindle 23, from a stop 26 to a co-operating fixed contact 27. Conveniently the force exerted by the controlling spring may be regulated for example, by a pointer moving over a calibrated scale. It may also be arranged for the force exerted by the closing or/and opening magnet to be adjustable. The two relays are similarly adjusted and the coil 21 of the closing electromagnet of the relay 18 and the coil 20 of the opening electromagnet of the relay 19 are connected in series with one another and on the side of the choker 15 nearer the alternator 6 to the conductors 13 and 14 joined to two phases of the said alternator, whilst the coil 21 of the closing electromagnet of the relay 19 and the coil 20 of the opening electromagnet of the relay 18 are connected in series with one another and on the side of choker 15 nearer the alternator 5 to the conductors 13 and 14 joined to two phases of the said alternator. The contacts of the relays 18 and 19 are connected in series with the operating coil 17 of the synchronizing contactor 16 across the busbars 10 and 11, the circuit including conductor 23, coil 17, conductor 29, contacts 25, 27 of relay 18, conductor 30, contacts 25, 27 of relay 19 and conductor 31.

In operation, when it is wished to effect synchronization of the alternators 5 and 6 and of the engines 1 and 2 the field windings of the alternators are energized with the same value of excitation current and the engine speeds are adjusted until the voltage of one alternator is not very different from the voltage of the other alternator, for as long as the closing electromagnet of one of the relays 18 and 19 fails to overcome the combined force of the controlling spring 24 and of the opening electromagnet the contact 25 of that relay remains open. When, however, the voltages of the alternators attain suitable relative values, for example, when one voltage differs by not more than five to ten percent from the other voltage, the circuit of the coil 17 of the synchronizing contactor is completed through the contacts 25, 27 of the two relays 18 and 19, and the contactor 16 closes, thereby connecting together the alternators 5 and 6 through the choker 15, and the alternators tend to synchronize.

The synchronizing operation is completed through short-circuiting of the choker 15 by closure of a running contactor 32 the operating coil 33 of which is connected across the busbars 10 and 11, the circuit including conductor 34, coil 33, conductor 35, preventive contacts 36 that are closed only when the moving parts of the two engines are in or substantially in the proper relative positions, conductor 37, the contacts 38 of a synchronizing relay 39, conductor 40, auxiliary contacts 41 of the contactor 16 and conductor 42. The auxiliary contacts 41 of the synchronizing contactor 16 close with a time lag when the

synchronizing contactor closes and prevent the circuit through the coil 33 of the running contactor being made before the synchronizing relay 39 has had time to operate. The moving auxiliary contact 41 may, for example, be connected with the main moving part of the contactor 16 through a spring 43 and operate under the control of a dashpot or similar device 45 which retards movement of the said contact to the closed position. The synchronizing relay 39 is of the contactor type and the contacts 38 thereof are normally closed, the operating coil 44 of the relay being connected across one phase of the choker 15. The sensitivity of the synchronizing relay is such that only when the alternators 5 and 6 are near their synchronous positions and the voltage across the choker 15 is zero or substantially zero, does the relay close, whereupon, provided the preventive contacts 36 are closed, the alternators are synchronized by closure of the running contactor 32.

The preventive contacts 36 and the mechanism for operating them in common with other parts of the synchronizing gear may take various forms, but in Figure 2 a knife-edged moving contact 46 is adapted to enter in between and to connect together two spring contacts 47 which are normally separated and are further separated by the contact 46 when the latter enters between them. The contact 46 is mounted on the frame or casing 48 of a differential gear comprising one or more planet wheels 49 rotatably mounted in the casing and meshing with two similar oppositely arranged bevel wheels 50 and 51 also rotatably mounted in the casing 48 and driven respectively by the shafts 52 and 54 having bearings 53 and 55 provided on the end of the engine 1. The shaft 52 is driven from the half-time shaft 56 of engine 1 through mitre gear 57 and the shaft 54 is driven from the half-time shaft 58 of the engine 2 through the mitre gears 59, 62 and 64, the shaft 60 provided with bearings 61 on the end of the engine 2 and the shaft 63 mounted in bearings 65. The arrangement is such that when the engines 1 and 2 run in opposite directions at equal speeds the bevel wheels 50 and 51 also run in opposite directions at equal speeds. Moreover, the speeds at which the shafts 52 and 54 are driven are twice the speeds of the half-time shafts 56 and 58 respectively.

It will be clear that if the shafts 52 and 54 rotate at different speeds the casing 48 will rotate with a velocity equal to half the difference between the speeds of the two shafts, whilst if the shafts rotate at equal speeds the casing remains stationary. Furthermore, when the half-time shafts 56 and 58 are in predetermined relative positions relatively to one another, the casing 48 is in a corresponding known position. It therefore follows that when the shafts 56 and 58 and the reciprocating parts of the engines 1 and 2 are in similar positions the moving contact 46 is in a predetermined position and it is arranged that only when the contact 46 is in or substantially in the said position does it engage the contacts 47 and allow synchronization of the alternators 5 and 6 to take place. Once the alternators are synchronized the contact 46 remains in its operative position and since the contacts 25, 27 of the relays 18 and 19 and hence the synchronizing contactor 16 and its auxiliary contacts 41 remain closed the energization of the coil 33 of the running contactor 32 is maintained. If desired the contactor 32 could be provided with auxiliary contacts adapted upon closing of

the contactor to interrupt the circuits of the coils 20, 21 of the relays 18 and 19 and to complete a maintaining circuit for its coil 33. It may be arranged for the moving contact 41 to have more than one predetermined position, for example, the shafts 52 and 54 may be driven at speeds equal to those of the half-time shafts 56 and 58 respectively, in which case there will be two diametrically opposite positions at which two pairs of contacts 47 connected in parallel may be provided severally at such positions for cooperating with the moving contact 46.

In Figure 3 the preventive contacts 66 and 67 are respectively mounted on sliprings 68 and 69 severally secured on the ends of shafts 70 and 71, from which they are insulated, and cooperating with the brushes 72 and 73. The shafts 70 and 71 are in alignment and are driven from the half-time shafts 56 and 58 of the engines 1 and 2 in a manner similar to that in which the shafts 52 and 54 of Figure 2 are driven, but in this case the shafts 71 and 70 are driven in the same direction. The gearing is so arranged that the shafts 71 and 70 respectively run at the same speeds as the shafts 56 and 58.

The contacts 66 and 67 are arranged at a definite relative position of the shafts 70 and 71 to engage one another and clearly such position of the shafts 70 and 71 corresponds to a definite relative position of the shafts 56 and 58. Furthermore, the contacts 66 and 67 are so positioned on the shafts 70 and 71 that when the contacts engage the engines 1 and 2 are in similar positions and corresponding cylinders fire simultaneously. For the sake of clarity the contacts 66 and 67 are shown mounted on spring arms but in practice one of the contacts would be mounted with its contact face flush with the surface of a disc or cylinder of insulating material carried by the driving shaft so that the other contact would press against and move smoothly over the surface of the disc or cylinder and the contact face. Once the alternators 5 and 6 are synchronized the contacts 66 and 67 move together in engagement with one another.

In Figure 4 mounted on but insulated from the half-time shafts 56 and 58 are the sliprings 75 and 74 respectively cooperating with the brushes 81 and 80, and provided with the arms 77 and 76 carrying the brushes 79 and 78. The brushes 78 and 79 move over the inner surfaces of the axially extending insulated segments 83 of the commutators 85 and 86.

Each commutator is provided with thirty segments and the successive segments 82 of the commutator 85 proceeding in a clockwise direction are respectively connected by conductors 84 to successive segments 83 of the commutator 86 proceeding in a counter-clockwise direction. It follows that when the brushes 78 and 79 are on interconnected segments 82 and 83 there is a circuit between the brush 80 and the brush 81 through slipring 74, arm 76, brush 78, the said segments and a conductor 84, brush 79, arm 77 and slipring 75. The arms 76 and 77 are so positioned relatively to the half-time shafts 58 and 56 that such circuit is made only when the reciprocating parts of corresponding cylinders of the engines are in or approximately in similar positions in their cycles of operations. It will be understood that the preventive contacts may be closed when the said parts are, say, within plus or minus 7½% of the predetermined relative positions. The brushes 78 and 79 are arranged to engage one segment 82 or 83 before leaving another segment

and it therefore follows that when the engines are running in synchronism the circuit through the preventive contacts is maintained.

In Figure 5 the armatures 90 of the auxiliary generators 87 and 88 are mounted on the ends of the half-time shafts 56 and 58 of the engines 1 and 2. The generators 87 and 88 are similar to magnetos and comprise permanent magnets 89 and two-pole shuttle type armatures 90 the windings 91 of which are connected through sliprings 92 and 93 to brushes 94 and 95. The windings 91 of the generators 87 and 88 are connected through the brushes 94 and 95 in series with the winding 97 of a relay provided with preventive contacts 98 and in series with a current limiting choke 96, the arrangement being such that when the corresponding cylinders of the two engines are firing simultaneously the armatures 90 are in similar positions and the voltages of the two generators 87 and 88 in the circuit of the winding 97 are equal and opposite. The moving contact 98 is biased to the close position, but if the moving parts of the two engines are far removed from their correct relative positions in their cycles of operation, since the voltages of generators 87 and 88 are not opposite in phase, a current flows through the coil 97 and effects opening of the contacts 98 and the contacts are maintained open until the moving parts of the engines including the half-time shafts 56 and 58 are near their proper relative positions when the contacts reclose.

In operation, when the ship has been manœuvred out of port, the engines are synchronized merely by exciting the field windings of the alternators 5 and 6 and adjusting the engine throttles until the engine speeds are nearly the same but one engine is very slowly overtaking the other by revolving at a slightly greater speed such as $\frac{1}{3}$ of a cycle per second greater, whereupon the engines having attained or nearly attained the condition in which their reciprocating parts and half-time shafts 56 and 58 are in similar positions the alternators automatically synchronize and cause the engines to run synchronously.

With an arrangement using protective contacts as shown in Figure 2, for example, the operator may, if he wishes, expedite the synchronizing process by watching the moving contact and by slightly speeding up an engine until the contact is nearly in the permissive position and by then adjusting the throttle and engine speed to that most favourable for effecting synchronization.

Conveniently a synchronizing lamp or similar device is provided and also an ammeter or wattmeter for indicating the current or power flow between the alternators 5 and 6 and when the alternators and engines have synchronized the operator may adjust the throttle of an engine to ensure that the engines are properly sharing the load. One great advantage of coupling together the engines electrically as described above is that power may be transferred electrically from one shaft to the other and this operates to equalize the shaft speeds in a storm when the load on one shaft may tend suddenly to vary greatly.

The alternators may be utilized for supplying electrical power for auxiliary services, and in such case their capacity may be suitably increased. The power may be withdrawn directly or through converting apparatus and suitable voltage regulating means will generally be provided.

Suitable protective arrangements will, of course, be provided for protecting the apparatus.

The invention may be applied to engines forming part of the gear of an electric system of ship propulsion, for example, the engines 1 and 2 might be arranged to drive the propellers through direct current motors supplied with power from generators coupled to the engines. Or the invention may be applied to reciprocating pumps or engines mounted on a common structure on land.

We claim:—

- 10 1. In an arrangement of the kind specified in which a pair of engines drive respectively a pair of synchronous dynamo electric machines arranged to be paralleled so that the engines rotate at the same speed, apparatus comprising a current limiting device, switching means for connecting the machines in parallel through the current limiting device, means responsive to the voltages and therefore the relative speeds of the two machines and arranged to operate the switching means to connect the machines in parallel through the current limiting device when the voltages of the machines are approximately equal, further switching means arranged when operated to connect the machines in parallel independently of the current limiting device, means arranged to prevent effective operation of the further switching means until the first switching means are operated and means arranged to prevent effective operation of the further switching means until the engines are in synchronism.
- 15 2. In an arrangement of the kind specified in which a pair of engines drive respectively a pair of synchronous dynamo electric machines arranged to be paralleled so that the engines will rotate in parallelism and at the same speed, apparatus comprising speed responsive means arranged to be brought into action for tentatively paralleling the machines when they are running at approximately the same speed, members operated by the respective engines for joint cooperative action when the engines are paralleled and rotating at the same speed in corresponding phase relationship, and means for completing paralleling of said machines when the cooperative action of said members becomes effective, the cooperative action of said members continuing so long as said machines and the engines continue to operate in parallelism.
- 20 3. In an arrangement of the kind specified in which a pair of engines drive respectively a pair of synchronous dynamo electric machines arranged to be paralleled so that the engines will rotate in parallelism and at the same speed, apparatus comprising parallelizing means arranged automatically to effect a tentative paralleling of the dynamo electric machines when they are being driven in substantial synchronism and means operated by the respective engines for joint cooperative action to complete the paralleling of said machines when the latter are in synchronism, the last named means becoming effective only when the engines are also in synchronism.
- 25 4. In an arrangement of the kind specified in which a pair of engines drive respectively a pair of synchronous dynamo electric machines arranged to be paralleled so that the engines will rotate in parallelism and at the same speed, apparatus comprising speed responsive means arranged to be brought into action for tentatively paralleling the machines when they are running at approximately the same speed, members operated by the respective engines for joint cooperative action when the engines are paralleled and rotating at the same speed in corresponding phase relationship, and means for completing paralleling of said machines when the cooperative action of said members becomes effective, the cooperative action of said members continuing so long as said machines and the engines continue to operate in parallelism.
- 30 5. In an arrangement of the kind specified in which a pair of engines drive respectively a pair of synchronous dynamo electric machines arranged to be paralleled so that the engines will rotate in parallelism at the same speed, apparatus comprising a pair of circuit closing members operated by the respective engines to close an operating circuit when said members occupy definite positions relatively to one another, said circuit being closed only when the engines are in synchronism, that is paralleled in the same phase relationship, a paralleling relay operated by the closing of said circuit for paralleling said machines and voltage responsive means controlled by the electric conditions of the respective machines for completing said relay operating circuits so as to effect direct paralleling of said machines only when the voltages of the respective machines are substantially equal.
